DESIGN FOR A SHOE SOLE

Paul A. Sperry, New Haven, Conn.

Application February 19, 1938, Serial No. 75,261

Term of patent 14 years

To all whom it may concern:

Be it known that I, Paul A. Sperry, a citizen of the United States of America, residing at New Haven, county of New Haven, and State of Connecticut, have invented a new, original and ornamental Design for a Shoe Sole, of which the following is a specification, reference being had to the accompanying drawing, forming a part thereof.

Fig. 1 is a bottom plan view of a shoe sole embodying my new design; and

Fig. 2 is a longitudinal section on line 2—2 of Fig. 1.

The dominant feature of this design is the smooth bottom surface of the shoe sole with spaced zigzag lines formed as a result of slits in the surface, the sections formed between said slits being in contact when the sole is at rest.

I claim:

The ornamental design for a shoe sole, substantially as shown and described.

PAUL A. SPERRY.
